INVENTOR.

Clarence F. Vogel,

BY

Geo. Kimmel.

ATTORNEY.

UNITED STATES PATENT OFFICE.

CLARENCE F. VOGEL, OF ROCK ISLAND, ILLINOIS.

HAIRPIN.

Application filed July 17, 1926. Serial No. 123,102.

This invention relates to hair pins and has for its particular object the provision, in the manner as hereinafter set forth, of a hair pin designed to grip or clamp the hair 5 to prevent accidental misplacement of the pin.

Another object of the invention is the provision, in a manner as hereinafter set forth, of a hair pin so designed that a mass 10 of the hair will be drawn together and gripped by a pair of legs of the pin.

The invention will be best understood from a consideration of the following detailed description taken in connection with 15 the accompanying drawing forming a part of this specification, with the understanding that the invention is not confined to any strict conformity with the showing of the drawing but may be changed and modified 20 so long as such changes and modifications mark no material departure from the salient features of the invention as expressed in the appended claims.

In the drawing:—

25 Figure 1 shows the pin embodying this invention in front elevation.

Figure 2 is a side view of the same and,

Figure 3 is a transverse section taken upon the line 3—3 of Figure 1.

30 Referring now to the drawing in detail wherein like numerals of reference indicate corresponding parts throughout the several views, the pin embodying this invention is shown as comprising a central penetrating body 1 which is formed of a pair of wire bodies twisted together in the manner shown and having one end of one body secured 35 to the adjacent end of the other body to form the blunt point 2.

40 At the other end of the penetrating member 1, the ends of the wire bodies forming this member are directed laterally of the body, in opposite directions, setting up the shoulder portion 3.

45 These lateral shoulder portions 3 merge into the downwardly directed upper leg portions 4 which lie upon opposite sides of and substantially parallel with the center penetrating member 1, as shown in Figure 1.

50 These portions 4 form the upper portion of a downwardly extending leg member indicated generally by the numeral 5 and as above described form the upper one of three distinct portions of a leg.

55 The portion 4 of each leg merges into a central corrugated portion 6 and each of

these portions 6 terminates in the outwardly and downwardly directed lower straight terminal portion 7. The intermediate corrugated portions 6 of the legs are arranged in cross relation and the lower portion of the central penetrating member 1 is located between the legs at the crossing point, as is clearly shown in Figure 3. From this disposition of the central portion 6 of the legs, 60 it will be seen that the lower terminal portions 7 of the legs are arranged in downwardly divergent relation.

Although the foregoing description has referred to separate portions of the hair pin, 65 it will be readily apparent from the showing of the drawing that the hair pin constructed in accordance with this invention may be formed of a single piece of hair pin wire and is started by bending the wire 70 centrally upon itself and twisting the same adjacent the bent portion thereby forming the penetrating member 1. The untwisted portions are then bent outwardly to form the shoulders 3 and the remaining portions 75 turned in substantially parallel relation to the portion 1 and formed to set up the legs 5 in the manner shown and described.

80 From the foregoing description it will be readily seen that when a hair pin constructed in accordance with this invention is forced through the hair, the divergent straight portions 7 of the legs will tend to gather together a large quantity of hair and this mass of hair will be straddled by the 85 legs 5 and penetrated by the central penetrating member 1. This will bring the mass of hair into the closed end of the hair pin, 90 between the central body 1 and the side portions 4 of the legs, and against the shoulders 95 3. The spring tendency of the legs to press 100 against the portion 1 lying therebetween, will thus lock the pin in the hair and therefore the accidental displacement of the pin is almost impossible.

Having thus described my invention what I claim is:—

1. A hair pin of the character described, comprising a central body, and a pair of leg members attached at one end to said body 105 and arranged in cross relation one on each side of the body to set up a clasping action.

2. A hair pin of the character described, comprising a central body, and a pair of leg members secured at one end to one end of 110 said body, said legs for a portion of their length lying substantially parallel with the

body, the remaining portions being arranged in crossed relation one on each side of the central body.

3. A hair pin of the character described, comprising a central penetrating body, a pair of laterally extending shoulders at one end of said body, and a leg extending from the outer portion of each shoulder, each substantially parallel with the body at its upper end, said legs being arranged in crossed relation beyond the said parallel end and lying one on each side of the body.

4. A hair pin of the character described, comprising a central body, and a pair of leg members secured at one end to one end of said body, said legs for a portion of their length lying substantially parallel with the body, the remaining portions being arranged in crossed relation one on each side of the central body, each of said legs terminating

in an outwardly and downwardly directed portion, said portion being arranged in divergent relation with respect to one another.

5. A hair pin of the character described, comprising a central penetrating body, a pair of laterally extending shoulders at one end of said body, and a leg extending from the outer portion of each shoulder, each substantially parallel with the body at its upper end, said legs being arranged in crossed relation beyond the said parallel end and lying one on each side of the body, each of said legs terminating in an outwardly and downwardly directed portion, said portion being arranged in divergent relation with respect to one another.

In testimony whereof, I affix my signature hereto.

CLARENCE F. VOGEL.
